US0D1080282S

(12) **United States Design Patent** (10) **Patent No.:** **US D1,080,282 S**
(45) **Date of Patent:** **** Jun. 24, 2025**

(54) **CHAIR BACKREST**

(71) Applicant: **Dehua Liang**, Zhongshan (CN)

(72) Inventor: **Dehua Liang**, Zhongshan (CN)

(**) Term: **15 Years**

(21) Appl. No.: **29/813,865**

(22) Filed: **Nov. 2, 2021**

Related U.S. Application Data

(63) Continuation-in-part of application No. 29/803,831, filed on Aug. 16, 2021, now Pat. No. Des. 996,877.

(30) **Foreign Application Priority Data**

(57) **CLAIM**

The ornamental design for a chair backrest as shown and described.

DESCRIPTION

FIG. 1 is a perspective view of a chair backrest showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings depict portions of the chair backrest that form no part of the claimed design.

1 Claim, 8 Drawing Sheets
